UNITED STATES PATENT OFFICE.

OSCAR KNOCH, OF ESSEN-ON-THE-RUHR, GERMANY, ASSIGNOR TO FRIED. KRUPP AKTIENGESELLSCHAFT, OF ESSEN-ON-THE-RUHR, GERMANY.

GUN WITH REVERSIBLE SHOULDER-PIECE.

1,162,933.

Specification of Letters Patent.

Patented Dec. 7, 1915.

Application filed February 13, 1913, Serial No. 748,194. Renewed February 10, 1914. Serial No. 817,880.

To all whom it may concern:

Be it known that I, OSCAR KNOCH, residing at Essen-on-the-Ruhr, Germany, a subject of the Emperor of Germany, have invented a certain new and useful Improvement in Guns with Reversible Shoulder-Pieces, of which the following is a specification.

This invention relates to guns with shoulder piece and consists in a particular arrangement of the shoulder piece.

One embodiment of the invention has been illustrated in the accompanying drawing, wherein—

15 Figure 1 is a side view, partly in section, of gun and mount, with the gun in horizontal position and Fig. 2 a similar view to Fig. 1, with the gun in high elevation.

The gun has a pedestal A, wherein the 20 forked pivot B is mounted with its vertical pivot pin b¹. The forked pivot has bearings for the horizontal trunnions c¹ on the cradle C, which latter carries the gun barrel D.

A shoulder piece E is supplied for aiming 25 the gun, which shoulder piece near one end thereof is mounted on a stock e¹. The stock e¹ is carried, by means of its journal e², in a socket c² provided on the cradle C, and may be secured in two different positions 180° 30 apart, by a lock bolt c³. The axis of the socket c² intersects the horizontal axis of the trunnions c¹ at an angle of 90°. The rest e³ of the shoulder piece E, against which the sighting gunner leans, is curved concentric 35 to the axis of the trunnion c¹.

If the gun has to be fired under depression or under slight elevation, the shoulder piece E takes the position relative to the gun indicated in Fig. 1, wherein the rest e³ hangs 40 below the stock e¹. The gun may then be aimed conveniently, up to an elevation of some 20° by the sighting gunner leaning with his shoulder against the rest e³. If the gun on the other hand has to be fired at high 45 elevation, the stock e¹ is first turned 180° in the socket c² after removing the lock bolt c³, whereupon it is again secured by the lock bolt c³. The rest e³ of the shoulder piece E is then situated above the stock e¹, see Fig. 2, 50 so that the sighting gunner may conveniently lay the gun, by means of the shoulder piece, up to the highest elevation.

The described arrangement of the shoulder piece offers the advantage, that the gun 55 may conveniently be given any elevation by

means of this comparatively short shoulder piece, measured in the length direction of the rest e³.

I claim:

1. A reversible shoulder piece for guns, comprising a shoulder rest and a stock for carrying said rest; the axis of said stock intersecting the axis of the horizontal gun trunnion, said shoulder rest being curved concentric to the trunnion axis and constructed to be turned around said stock axis and to be secured in either of two opposite positions in the same vertical plane. 65

2. A reversible shoulder piece for guns, comprising a shoulder rest and a stock for carrying said rest; the axis of said stock intersecting the axis of the horizontal gun trunnions, said shoulder rest being curved concentric to the trunnion axis; a socket for said stock on a part that partakes of the elevation of the gun, a key for locking said stock in said socket; said shoulder piece constructed to be turned in said socket and secured by said key in two opposite positions in the same vertical plane. 70

3. A reversible shoulder piece for guns, comprising a shoulder rest and a stock for carrying said rest; the axis of said stock intersecting the axis of the horizontal gun trunnions, said shoulder rest being curved concentric to the trunnion axis; a socket for said stock on a part that partakes of the elevation of the gun, a key for locking said stock in said socket; said shoulder piece constructed to be turned in said socket and secured by said key in two opposite positions in the same vertical plane. 75

80

3. A reversible shoulder piece for guns, comprising a shoulder rest and a stock for carrying said rest; the axis of said stock intersecting the axis of the horizontal gun trunnions, said shoulder rest being curved concentric to the trunnion axis; a socket for said stock on a part that partakes of the elevation of the gun, a key for locking said stock in said socket; said shoulder piece constructed to be turned in said socket and secured by said key in two opposite positions in the same vertical plane; whereby it will be possible to conveniently lay the gun in any elevation from lowest depression to highest elevation. 95

4. A shoulder piece for guns, comprising a shoulder rest and a stock for carrying said rest; the axis of said stock intersecting the axis of the horizontal gun trunnion, said shoulder rest being curved concentric to the trunnion axis and constructed to be turned around said stock axis and to be secured in either of two opposite positions in the same vertical plane. 100

5. A shoulder piece for guns, comprising a shoulder rest and a stock for carrying said rest; the axis of said stock intersecting the axis of the horizontal gun trunnions, said shoulder rest being curved concentric to the trunnion axis; a socket for said stock on 110

a part that partakes of the elevation of the gun, a key for locking said stock in said socket; said shoulder piece constructed to be turned in said socket and secured by said

5 key in two opposite positions in the same vertical plane.

6. A shoulder piece for guns, comprising a shoulder rest and a stock for carrying said rest; the axis of said stock intersecting the 10 axis of the horizontal gun trunnions, said shoulder rest being curved concentric to the trunnion axis; a socket for said stock on a part that partakes of the elevation of the gun, a key for locking said stock in said 15 socket; said shoulder piece constructed to be turned in said socket and secured by said key in two opposite positions in the same vertical plane; whereby it will be possible to conveniently lay the gun in any elevation 20 from lowest depression to highest elevation.

7. A shoulder piece for guns comprising a shoulder rest and a member connecting the shoulder rest with the gun cradle; a receiver 25 on the gun cradle for said member, said member having two positions in the receiver, whereby said shoulder rest may be positioned below said member for low gun elevation and above said member for high 30 gun elevation, both said positions being in the same vertical plane, said shoulder rest being curved concentric to the axis of the horizontal gun trunnions.

8. A shoulder piece for guns, comprising 35 a shoulder rest and a stock therefor, a socket on the gun cradle constructed to receive the end of said stock; said end having two selective positions in said socket whereby said shoulder rest may be positioned below said

stock for low gun elevations and above said 40 stock for high gun elevations, said shoulder rest being curved concentric to the axis of the horizontal trunnions of the gun.

9. A shoulder piece for guns, comprising a shoulder rest and a stock therefor, a socket 45 on the gun cradle constructed to receive the end of said stock; said end having two selective positions in said socket whereby said shoulder rest may be positioned below said stock for low gun elevations and above said 50 stock turned 180° relative to said first position for high gun elevations; and means for locking the shoulder piece in any one of said positions, said shoulder rest being curved concentric to the axis of the horizontal 55 trunnions of the gun.

10. A shoulder piece for barrel recoil guns comprising a shoulder rest and a stock connecting the shoulder rest with the gun cradle, said shoulder rest having two stationary positions by means of said stock allowing the shoulder rest to be positioned below said stock for low gun elevations and above said stock for high gun elevations, said stock being inclined in regard to the longitudinal axis of the gun barrel in such a manner that the connecting point between said shoulder rest and its stock in any one of said positions of the shoulder rest lies above said axis of the gun barrel.

The foregoing specification signed at Bar-
men, Germany, this 31st day of January,
1913.

OSCAR KNOCH. [l.s.]

In presence of—

HELEN NUFER,
ALBERT NUFER.
